UNITED STATES PATENT OFFICE.

EDWARD WHALLEY, OF WASHINGTON, DISTRICT OF COLUMBIA.

DESIGN FOR A TILE.

SPECIFICATION forming part of Design No. 18,375, dated June 5, 1888.

Application filed April 24, 1888. Serial No. 271,741. Term of patent 14 years.

To all whom it may concern:

Be it known that I, EDWARD WHALLEY, a subject of the Queen of Great Britain, residing at the city of Washington, in the District of Columbia, have invented and produced a new and original Design for Tiling, of which the following is a specification, reference being had to the accompanying drawing, forming a part thereof, representing a plan view of my newly-designed tile.

My design consists of a tile, A, having its upper edge, a , in a right line, from which extend at right angles thereto side edges, $a' a'$, these described lines constituting the upper member, T, of the design. From the lowermost point of each side $a' a'$, and extending from each of said points obliquely toward a central point, a^2 , the perimeter of the tile fol-

lows a sinuous line, a^3 , composed of an inwardly and outwardly diverging curve, $c c'$, 20 the lowermost curves from either side conjoining at the common central point, a^2 , and these curvilinear lines define and describe the lower member, T', of the tile of the shape commonly known in the arts as a "scallop." 25

I claim—

The within described design for a tile, the perimeter of which is composed of an upper right line, a , sides $a' a'$ at right angles thereto, and springing from each of said sides sinuous 30 lines a^3 , composed of obverse and reverse curves $c c'$, as shown.

EDWARD WHALLEY.
